ATTORNEY.

UNITED STATES PATENT OFFICE

GEORGE E. WADSWORTH, OF ERLANGER, KENTUCKY, ASSIGNOR TO THE EARL ELECTRIC MFG. COMPANY, OF CINCINNATI, OHIO, A CORPORATION OF OHIO

FUSE MOUNTING BLOCK

Application filed January 22, 1931. Serial No. 510,429.

My invention relates to fuse mounting blocks, and particularly what are technically known as fuse contact bases of the type adapted to receive knife-blade contact type 5 cartridge fuses.

The usual fuse contact base for receiving a knife blade contact type cartridge fuse comprises a mounting block with resiliently mounted clamping jaws providing terminal 10 connections for receiving the blades of the cartridge fuses. If the contact jaws become bent or lose their resiliency by being pried too far apart, the cartridge fuse is insecurely mounted so that a good connection is not 15 established, or if a connection is established, it is through restricted areas on the surfaces of the knife blades of the fuses. Poor contact with the blades of the fuses results in heating up the fuses due to insufficient surface contact to overcome the resistance load 20 of the contact mounting. Fuses of this type frequently burn out and cause difficulty due to insufficient contact.

To overcome this difficulty it is old to provide 25 detachable clamps which are inserted over the opening in the clamping jaws, and which can be tightened up to exert pressure against the clamping jaws to cause them to firmly grip the knife blades of the fuses. In 30 most fuse box mountings, the presence of such clamping devices interferes with the closing of the lids of the fuse boxes, or requires such clearance within the receptacle holding the fuse block as to be objectionable.

It is the object of my invention to provide a 35 fuse contact base, in which a clamping device is associated with the jaws which receive the blades of the fuse in such a manner that the jaws may be forced into position, causing contact with the blades over substantially the entire area of the blades.

Another object of my invention is to provide 40 clamping devices which form a permanent part of the fuse contact base.

As the contact jaws which form the terminals receiving the blades of the fuse tend to 45 spring apart at their open ends, it is further my object to provide a clamping device which exerts a thrust against the open ends 50 of the jaws, thereby causing the blades to seat

in alignment with the walls of the jaws so that thorough contact is established.

The above objects and other objects to 55 which reference will be made in the ensuing disclosure, I accomplish by that certain combination and arrangement of parts of which I have shown a preferred embodiment.

Referring to the drawing:

Figure 1 is a side elevation of a preferred 60 type of fuse cut out base, with the clamping device closed.

Figure 2 is a plan view of the fuse cut out base in the same position as is indicated in Figure 1.

Figure 3 is a perspective view of a portion 65 of a fuse cut out base showing one of the contact jaws with the clamping device associated with said jaws open to permit the ready insertion of the cartridge fuse.

On a mounting base 1, I have shown the 70 conductive blocks 2 secured to the base with terminal bolts 3. Extending up from the contact block 2, I have shown upright clamping jaws 4 and 5 respectively. The jaws 4 and 5 have outwardly bent lower portions 6 75 and 7 which may be secured to the conductive blocks 2, as with rivets 8.

A reinforcing strip 9 extends upwardly and engages the clamping jaw 5 adjacent its 80 upper end.

The clamping jaw 4 is mounted for movement to and from the clamping jaw 5.

As a particularly desirable clamping arrangement effective on the jaw 4, I have indicated mounting brackets 10, 11 having 85 flange portions 12, 13 which provide journals for a pin 14, which extends across between the flange portions 12, 13 and secures the end of a toggle link 15.

An actuating handle 16 is provided, pivoted at 17 in bosses 18, 19, which are mounted with rivets, or other suitable mechanical connections on the outwardly extending flange portion 6 of the clamping jaw. The handle 16 is linked to the link 15 with a pivot 90 19.

When the handle 16 is moved in a counter-clockwise direction, as indicated at Figure 3, the toggle links composed of the portion of the handle 16 between the pivot 17 and the pivot 19 and the long toggle link 15, move 95 100

toward straightened out position, thereby causing the upper end of the contact jaws to be firmly pressed together so that good surface contact between the inner surface of the 5 jaws and the outer surfaces of the blades of the cartridge fuse is established.

The cartridge fuse for which I have provided this special mounting comprises a body 20, through which the resistance element 10 passes, and having caps 21 from which extend the blades 22.

In actuating my improved fuse contact base, the handle 16 of the clamping device is opened out at each end, as indicated in Figure 3. The fuse is then inserted into the clamping jaws, and when the handle 16 is pressed to the left, as shown in Fig. 3, the toggle links straighten out, causing pressure to be exerted against the upper end of the 20 clamping jaw. This causes firm surface engagement between the inner surface of the contact jaws and the outer surfaces of the blades with the fuses. To release the cartridge fuses, the clamping devices are rocked 25 to the right, as indicated in Figure 3, and the cartridge fuse may be readily removed.

While I have only shown one particular type of blade clamping jaw, and while I have only shown one particular type of 30 clamp, it should be understood that mechanical variations in the particular type of the clamping device rests within the scope of my invention. It should further be understood that other methods for reinforcing the 35 clamping jaws of the permanent mountings than by the use of an inclined brace, such as is indicated at 9 in Figure 3, might be employed.

With the simple construction which I have 40 illustrated, the increase in cost of the fuse contact base is so slight in proportion to the economies permitted that the construction is capable of widespread commercial use.

Having thus described my invention, what 45 I claim as new and desire to secure by Letters Patent, is:—

1. A fuse cut out base having spaced pairs

of contact jaws, and having clamping devices associated with one of the jaws of each pair for insuring uniform surface bearing of said jaws on the sides of the blades of a knife-blade contact type cartridge fuse, and said clamping devices comprising toggle links with a lever handle arranged to straighten out said toggle links after the insertion of the blade of the fuse. 70

2. A fuse cut out base having spaced pairs 75 of contact jaws, and having clamping devices associated with one of the jaws of each pair for insuring uniform surface bearing of said jaws on the sides of the blades of a knife-blade contact type cartridge fuse, and said clamping devices comprising toggle links with a lever handle arranged to straighten 80 out said toggle links, said clamping devices being arranged at the sides of the jaws.

3. In a knife blade contact type cartridge 85 fuse mounting block, a pair of spaced contact jaws having permanently mounted clamping devices associated therewith for clamping said jaws together after the insertion 90 therein of the blades of a cartridge fuse, said clamping devices arranged to exert clamping pressure close to the open ends of said jaws, and said clamping devices comprising toggle links, one of which is extended 95 to provide a handle for straightening out said toggle links, thereby exerting pressure to clamp said jaws together.

4. A fuse cut out base having spaced pairs 100 of blade contact jaws, one of each pair of jaws having a link pivoted at right angles to the jaws adjacent its outer end, and a lever 105 pivotally connected to said link, said lever being pivotally mounted whereby a portion of said lever forms a toggle link with said first noted link.

5. A fuse cut out base having spaced pairs 110 of blade contact jaws, with means permanently mounted at the sides of said jaws for clamping said jaws together after the insertion of said blades, said means comprising toggle links. 110

GEORGE E. WADSWORTH.
